Primary Examiner — Eric Goodman*Assistant Examiner* — Dana K Weiland(74) Attorney, Agent, or Firm — Mitchell Law PLLC;
Matthew W. Mitchell(57) CLAIM

The ornamental design for footless kneehigh sock with trim, as shown.

DESCRIPTION

FIG. 1 is a front view of the footless kneehigh sock with trim of the present invention; and,
FIG. 2 is a side view thereof.

The broken lines on the sock represent stitching and form a part of the claimed design. The additional broken lines in the views are directed to environment and form no part of the claimed design.
